SPEAKER GRILL

John Anchel, Milford, Pa., assignor to Sparkomatic Corporation, Milford, Pa., a corporation of Pennsylvania
Continuation of design application Ser. No. 12,894,
July 25, 1968. This application Oct. 13, 1969, Ser.
No. 19,792

Term of patent 14 years

Int. Cl. D14—01, 99
U.S. Cl. D26—14

FIG. 1 is a front elevation of a speaker grill showing my new design;

FIG. 2 is an end elevation thereof;

FIG. 3 is a side elevation thereof;

FIG. 4 is a section taken on line 4-4 of FIG. 1;

FIG. 5 is an enlarged fragmentary section taken on line 5-5 of FIG. 1;

FIG. 6 is an enlarged fragmentary corner disclosed for clarity of illustration;

FIG. 7 is a front elevation of a modified embodiment of the speaker grill illustrated in FIG. 1;

FIG. 8 is an end elevation thereof;

FIG. 9 is a side elevation thereof;

FIG. 10 is a section taken on line 10-10 of FIG. 7;

FIG. 11 is an enlarged fragmentary section taken on line 11-11 of FIG. 7; and

FIG. 12 is an enlarged fragmentary corner disclosed for clarity of illustration.

The shading is intended to indicate contrasting colors.

This application is a continuation of my copending design application Ser. No. D. 12,894, filed July 25, 1968 and now abandoned.

I claim:

The ornamental design for a speaker grill, as shown and described.
